UNITED STATES PATENT OFFICE.

EZRA A. MATHERS, OF PHILADELPHIA, PENNSYLVANIA, ASSIGNOR OF ONE-HALF TO
DANIEL W. HARNER, OF PHILADELPHIA, PENNSYLVANIA.

ORE-CRUSHER.

1,017,780.

Specification of Letters Patent. Patented Feb. 20, 1912.

Application filed June 20, 1906. Serial No. 322,655.

To all whom it may concern:

Be it known that I, EZRA A. MATHERS, a citizen of the United States, residing at Philadelphia, in the county of Philadelphia and State of Pennsylvania, have invented 5 certain new and useful Improvements in Ore-Crushers, of which the following is a specification.

My said invention consists of an improved 10 construction of a crusher and pulverizer particularly adapted for pulverizing and crushing ores preparatory to smelting and refining, and it consists in various improvements in the details of construction and arrangement of parts whereby not only a very 15 efficient machine is provided for the purpose but one that is also comparatively inexpensive to construct and operate, all as will be hereinafter more fully described and 20 claimed. Referring to the accompanying drawings which are made a part hereof and on which similar reference characters indicate similar parts, Figure 1 is an end elevation of one of my improved crushers, 25 Fig. 2 a horizontal section on the dotted line 2—2 in Fig. 1, Fig. 3 a horizontal section on the dotted line 3—3 in Fig. 1, and Fig. 4 a central vertical section on the dotted line 4—4 in Fig. 1.

30 In said drawings the portions marked A represent the castings comprising the ends of the frame or casing of the machine, B the dust guards or casing, C the bearings for the rocking crusher, D said crusher, E 35 the stationary crusher, F the large pulverizing roller, and G, G' and G² the small pulverizing rollers.

The frame of the machine comprises the 40 end castings A, which are of suitable form and strength to afford the required supports and bearings for the several parts.

The dust guards or casing comprises the 45 plates B which are arranged across the end of the machine outside the small rollers G, G' and G² and also along the sides adjacent to the ends of said rollers and the large roller F. The end plate is supported on bolts b extending through a hook at its upper end and the ends A, and the side plates 50 are connected thereto by flanges b' riveted thereto, as shown in Fig. 2, and are otherwise supported by the connected parts of the machine.

The bearings C are suitable inwardly 55 extending flanges on the upper ends of the

castings A formed with suitable recesses to contain the rollers c, as best shown in Fig. 3.

The rocking crusher D is cylindrical in form and rests at its ends upon the rollers c. Its interior is hopper-shaped and is lined 60 with chilled steel corrugated plates D', which constitute crusher faces. Said plates D' have lugs d' which engage with recesses d in the adjacent faces of the part D and thus secure said parts together. A slot d⁵ 65 constituting a passage-way leads from the lower side of the hopper through part D and is adapted to discharge onto the side of roller F adjacent to the small roller G. At each end of part D a downwardly projecting radial lug D⁴ is formed, each of which has a frame or slide secured thereto, said slides being each composed of vertical bars D⁵ secured at their upper ends to each side of the lugs D⁴ by a bolt d⁴ and at their lower 70 end having a distance block D⁶ between them and secured together by a bolt d⁶ which passes through each bar and said distance block. A sliding block D⁷ is mounted to slide vertically between said bars and a cam 75 D² mounted on the shaft 1, near each side of the machine, is mounted and adapted to operate in an opening provided therefor in said block. Thus, as shaft 1 revolves the frame D⁵ is vibrated back and forth and 80 the crusher D is rocked upon the rollers c, block D⁷ sliding up and down in the way between the bars D⁵, as will be readily understood.

The stationary crushing member E is a 85 casting of the form best shown in outline by dotted lines in Fig. 1 and has a chilled corrugated crushing surface. It is supported by gudgeons e in each end which are mounted in bearings E' formed on the lower 90 ends of screw rods e', which extend upwardly through perforations in flanges a⁶ 95 on the ends of the castings A and are provided with nuts e² on their upper ends to afford the means of support and adjustment. Other nuts e³ are provided under the flanges 100 by which the rods may be held in any adjusted position and said crusher thus secured fixed in whatever position may be desired for the character of work to be done. Said gudgeons e extend through vertical slots a² in the castings A, which hold said crusher from vibration, and permit its vertical adjustment. Dust guard plates e⁴ are mounted on said gudgeons to cover said 105

slots, between the respective ends of the crusher and the adjacent casting A to prevent the dust and crushed ore from passing through said slots.

5 The crushing roller F is a large smooth-faced roller and is mounted upon the main shaft 1 immediately beneath the crushing members D and E. Said main shaft 1 is provided with a driving pulley 2 by which 10 power may be applied by a belt from any source provided.

The rollers G, G' and G² are each mounted upon shafts journaled in bearings on the inner ends of rods or arms g which project through flanges a⁵ on the castings A and have nuts g' on their outer ends. A plate g² is fixed to said rod g a short distance from the flange through which said bolt passes and a coiled spring g³ is interposed between said plate and said flange, thus serving to normally force the roller carried by the inner ends of said rods toward the main crushing roller F. The several shafts of said rollers project through 25 slots in the side plates B, which permit their adjustment. A casing g⁴ preferably surrounds each of said springs. By adjusting the nuts g, said rollers may be adjusted toward or from the face of said roller F, as 30 will be readily understood.

The carrier H is or may be an endless belt carrier of any approved form provided with suitable carrier flights and is mounted upon rollers h, h', on shafts suitably located to support said carrier beneath the crushing rollers. Its outer end is supported by a cable or any other suitable support H'.

The operation of my said invention is as follows:—The parts being in their respective positions, as illustrated in Fig. 1, the ore to be crushed is deposited in the hopper and passes between the faces of the crushing parts D and E, the corrugated chilled steel surfaces D' and E serve to 40 break and crush the lumps of ore as the rocking member D is rocked back and forth by means of its connection with the cams D² on the shaft 1. Said rocking member D is supported and its movements facilitated by 45 the roller bearings c as before described. The crushed ore passes through the opening d⁵ which extends through the lower part of the member D and drops upon the surface of the crushing roller F and is carried between said crushing roller and the coating rollers G, G' and G², by which it is pulverized and falls upon the endless carrier H beneath. Said endless carrier may be of any length or arrangement desired to carry 55 the pulverized material to the smelter or any other desired point. When it is desired to remove the roller F, it can be done by merely removing the belt wheel 2 and sliding said roller off the shaft 1 through 60 an opening in the casing B covered by a

plate B⁴ which is secured in position by means of bolts b⁴ as shown. The bolts d⁴ securing the frame D⁵ to the lugs D⁴ on the lower end of the rocking member D will also be removed in order to release said frame and the cam from engagement and free roller F. The face of the crushers may be renewed when worn by lifting out of the supporting bodies and putting new parts in their places as will be readily understood. 75 When it is desired not to pulverize the material the rollers G, G' and G² may be drawn away from the roller F so that the crushed or broken material will pass through without being pulverized. The degree of disintegration may be regulated by the adjustment of said rollers, as will be readily understood.

Having thus fully described my said invention, what I claim as new and desire to 85 secure by Letters Patent, is:—

1. In an ore crusher, the combination, of the frame, a hopper formed on the top thereof, a crushing member having a hopper-like recess with corrugated sides mounted in said 90 hopper and extending from side to side thereof formed cylindrical in cross section and with its ends mounted upon roller bearings in said frame and having an opening leading through its lower side, means to rock 95 said crushing member, and a second fixed crushing member mounted between the sides of said first crushing member, substantially as set forth.

2. In an ore crusher, the combination, of the frame formed with a hopper at its top, a rocking crushing member of unitary structure and of exterior cylindrical formation with a hopper-like recess longitudinally thereof lined with corrugated chills and 105 formed with an opening through its lower side for the discharge of the crushed material mounted within said hopper, means for rocking said member, and a second crushing member fixed in said recess of said 110 rocking crushing member, substantially as set forth.

3. In an ore crusher, the combination, of the frame formed with a hopper at its top, a rocking cylinder mounted in suitable bearings at each end in said frame and formed with a hopper-like recess in its top side the sides of which are provided with crushing faces and an opening leading therethrough to the lower part of the machine, and a 120 fixed crushing member mounted upon vertically adjustable bearings and located between the sides of said recess in said first crushing member, substantially as set forth.

4. In an ore crusher, the combination, of the frame, the hopper, a crusher in said hopper comprising a rocking crushing member and a fixed crushing member, a pulverizer beneath said crusher comprising a large roller mounted upon a driving shaft, 130

rollers mounted in adjustable bearings and
adapted to coact with said large roller,
means for driving said driving shaft, a cam
on said driving shaft, and a connection be-
5 tween said cam and the rocking crusher
member for rocking it, substantially as set
forth.

In witness whereof, I have hereunto set

my hand and seal at Washington, D. C.
this 14th day of June, A. D. nineteen hun- 10
dred and six.
